(57) **CLAIM**

The ornamental design for cooking appliance with low profile control panel, as shown and described.

DESCRIPTION

FIG. 1 is a perspective view of a cooking appliance with low profile control panel showing our new design;

FIG. 2 is a front view thereof;

FIG. 3 is a right side view thereof;

FIG. 4 is a left side view thereof;

FIG. 5 is a bottom view thereof;

FIG. 6 is a rear side view thereof; and,

FIG. 7 is a top view thereof.

The broken line showing of the cooking appliance is included for the purpose of illustration and forms no part of the claimed design.
